FESTOON RING

Warren B. S. Cameron, Hillsboro, R. I.

Application May 28, 1949, Serial No. 2,931

Term of patent 14 years

(Cl. D21—1)

To all whom it may concern:

Be it known that I, Warren B. S. Cameron, a citizen of the United States, residing at Hillsboro in the county of Kent, and State of Rhode Island, have invented a new, original, and ornamental Design for a Festoon Ring, of which the following is a specification, reference being had to the accompanying drawing, forming a part thereof, in which:

Fig. 1 is a view in front elevation, and

Fig. 2 is a plan view from below of a festoon ring, showing my new design.

I claim:

The ornamental design for a festoon ring, substantially as shown.

WARREN B. S. CAMERON.
